UNITED STATES PATENT OFFICE.

ROBERT J. W. HAMILL, OF BALTIMORE, MARYLAND, ASSIGNOR OF THREE-FOURTHS TO GEORGE W. EVANS, OF SAME PLACE.

LOCK-COVER FOR MILK-CANS.

SPECIFICATION forming part of Letters Patent No. 623,957, dated April 25, 1899.

Application filed January 21, 1899. Serial No. 702,880. (No model.)

To all whom it may concern:

Be it known that I, ROBERT J. W. HAMILL, a citizen of the United States, residing at Baltimore, in the State of Maryland, have invented certain new and useful Improvements in Lock-Covers for Milk-Cans, of which the following is a specification.

This invention relates to a lock for securing the covers on milk-cans.

10 The invention is illustrated in the accompanying drawings, in which—

Figure 1 is a side elevation of a milk-can, the cover of which is removed and shows the lock as it appears at one side of the collar. Fig. 2 is a diametrical section of the cover and shows the lugs which coact with the lock parts on the can. Fig. 3 is a side elevation of a milk-can, the cover of which is removed, and shows a recess on the side of the collar opposite that seen in Fig. 1. Fig. 4 is a diametrical section of the cover, being the side opposite that seen in Fig. 2, and shows a lug that coöperates with the recess seen in Fig. 3. Fig. 5 is a perspective view, on a larger scale, 25 of the locking-bolt shown in position on the collar in Fig. 1. Fig. 6 shows the collar with the bolt in the locked position.

The milk-can A may be of any preferred shape or size. A metal collar B surrounds 30 the top or neck of the can. At one side this collar has two circumferentially-extending grooves or recesses c and d, each of which has a right-angled branch c' and d', opening upward at the rim edge of the collar. One 35 of these grooves c c' is to receive the locking-lug c² on the cover, and the other groove d contains a locking-bolt e, which is movable or 40 slidably therein. This groove d and its right-angled entrance d' also receive the push-lug e' on the cover, which pushes the bolt e when the cover is partly rotated on the can-collar.

The locking-bolt e is confined to the groove d, in which it slides, by a thin piece of metal plate f, which keeps the bolt from falling out 45 when the cover is off. When this bolt is in the shot position, (see Fig. 6,) its point end g takes in a branch g' of the groove c. The bolt has one side faced with a thin sheet of rubber h, held by cement. This rubber prevents the bolt from slipping too easily, and

thereby insures that it will not slide back accidentally after it has been locked.

The cover I on the inside has an annular recess j adjoining the rim or down-flange k, and a suitable gasket l is in this recess. 55 When the cover is in position on the can-collar B, the gasket fits on the rim edge of the collar and serves to make a tight joint and prevent leakage of milk should the can be upset. Adjoining the locking-lug c² on the 60 down-flange k of the cover is a keyhole m. In practice a small slip of paper is inserted in the cover and over this keyhole, on the inside, before placing the cover on the milk-can. The lug c² on the cover takes in the groove-entrance c', and the other lug e' takes in the groove-entrance d' back of the bolt e. Then a partial rotation of the cover I causes the lug c² to pass along the groove c, whose upper edge is slightly inclined, and at the same 65 time the lug e' pushes the bolt along across the entrance c' and until the point end g of the bolt enters the branch groove g', and thereby completes the locking operation. Now if the cover be rotated in the reverse direction 70 the bolt e will not be retracted, but the locking-lug c² will come under the bolt, and hence cannot pass up and out of the entrance c', and thereby the cover will be locked to the can. In order to unlock it, the end of a suit- 75 ably-pointed instrument must be inserted from the outside through the hole m and puncture the slip of paper, and the end of said instrument will bear against the point end g of the bolt and be held there, and the latter may then be forced back to the unlocked 80 position by simply rotating the cover I in the reverse direction. Down to this point the lock parts at one side only of the collar and cover have been described; but those on the 85 opposite side (shown in Figs. 3 and 4) will 90 now be described.

The collar B at a point diametrically opposite the locking-bolt e has a circumferential groove n with entrance n' at the rim edge 95 and an inclined upper edge n² at the extremity of the groove. The cover on the inside of its down-flange k has a lug o, which passes into the entrance n' and then into the groove n and when the cover is partly rotated passes 100

finally into the extremity of the groove where the upper edge n^2 is inclined. This holds the cover down.

This invention is to operate similarly to 5 that shown and described in Letters Patent of the United States, granted George W. Evans August 4, 1885, No. 323,864, and is an improvement thereon.

Having thus described my invention, what 10 I claim as new, and desire to secure by Letters Patent, is—

1. The combination of a milk-can collar having a circumferentially-extending locking-groove, and a circumferentially-sliding bolt independent of the locking-groove but serving to guard the entrance of said groove; and a cover having a down-flange which takes over and surrounds the said collar—the down-flange being provided on the inside with a lug 15 which engages the locking-groove, and a second lug which pushes the bolt to the locked position when the cover is partly rotated.

2. The combination of a milk-can collar having a circumferentially-extending locking-groove, and a circumferentially-sliding bolt provided with a rubber facing to prevent the bolt from slipping accidentally; and a cover having a down-flange which takes over and surrounds the said collar—the down-flange being provided on the inside with a lug 25 which engages the locking-groove, and a second lug which takes back of said bolt and pushes the bolt to the locked position when the cover is partly rotated.

3. The combination of a milk-can provided

at the neck-opening with a collar; two circumferentially-extending grooves at one side of the collar; a sliding bolt located in one of said grooves; a circumferential groove in the collar diametrically opposite the groove carrying 40 the bolt; a cover having a down-flange and three lugs on the inside of the said down-flange said lugs registering with the entrances of the grooves on the collar, whereby when the cover is on a partial revolution of the cover will 45 cause two of the lugs to engage grooves and the other lug to coact with the bolt and lock the cover on the collar, as set forth.

4. The combination of a milk-can collar having a locking-groove provided with a right-angled branch, c' , and a parallel branch, g' ; a circumferentially-extending groove, d , having position above said locking-groove and coincident with said parallel branch; a sliding bolt in said upper groove and adapted to have 50 one end entered in the parallel branch; and a cover having a down-flange which surrounds said collar, said down-flange being provided on the inside with a lug which engages the locking-groove and a second lug which pushes 55 the bolt into the parallel branch when the cover is partly rotated, substantially as described.

In testimony whereof I affix my signature in the presence of two witnesses.

ROBERT J. W. HAMILL.
